FLY HOLDER

Edward E. Smith, Idleyld Park, Oreg.

Application May 29, 1940, Serial No. 337,912

9 Claims. (Cl. 43—32)

This invention relates to a novel holder or carrier for fly hooks or fishhooks and more particularly to a holder or carrier which may be worn on a hat or cap and which is provided with a plurality of supporting elements or tabs, each of which is adapted to removably mount a fly hook or fishhook in a manner so that the hook may be readily detached from its supporting tab or applied thereto.

Still a further aim of the invention is to provide an article of this character which may be economically manufactured and sold and which will be efficient and practical in use as well as durable.

Other objects and advantages of the invention will hereinafter become more fully apparent from the following description of the drawing, which illustrates preferred embodiments of the invention, and wherein—

Figure 1 is a side elevational view of a preferred embodiment of fly holder,

Figures 2 and 3 are transverse sectional views taken substantially along the planes of the lines 2—2 and 3—3, respectively, of Figure 1,

Figure 4 is a longitudinal sectional view taken substantially along the plane of the line 4—4 of Figure 1,

Figure 5 is a view similar to Figure 3 showing the tab folded for applying or removing a flyhook,

Figure 6 is a fragmentary side elevational view of a modified form of the invention,

Figure 7 is a transverse sectional view taken substantially along the line 7—7 of Figure 6, and

Figure 8 is a longitudinal sectional view taken substantially along the plane of the line 8—8 of Figure 6.

Referring more particularly to the drawing, wherein like reference characters designate like or corresponding parts throughout the different views, 10 designates generally the fly holder including a strap 11, provided with a conventional buckle 12, at one end thereof, for adjustably connecting the ends of the strap 11 to form a band adapted to be attached around the crown portion of a hat or cap, not shown, as for example over a conventional hatband.

A plurality of tabs or fly hook supporting elements 13 are provided with corresponding enlarged ends 14 which are attached to the strap 11 by means of staples 15, or other suitable fastenings, along the upper edge thereof. The opposite, free ends of the tabs 13 extend above the upper edge of the strap 11 and are provided with spaced apertures 16 which are adapted to fric-

tionally engage a fly hook 17, adjacent its barbed end 18, for mounting the hook, in the manner as illustrated in Figure 1. Tabs 13 are formed of a flexible material, preferably rubber, although leather, spring metal and other materials may be employed.

To apply a fly hook 17 to a tab 13 or to remove the hook therefrom, the tab 13 is folded between its apertures 16, as illustrated in Figure 5, so that the barbed end 18 can be passed through the substantially aligned apertures 16 to attach the hook to the tab or to detach it therefrom. When a hook 17 is thus attached to a tab 13 and disposed in the position, as illustrated in Figure 5, the tab 13 is released permitting its free end to spring outwardly to assume the position, as seen in Figure 1, for frictionally and yieldably engaging the shank portion of the hook, adjacent its barbed end 18 and to thereby effectively hold the hook.

A modified form of the tab, designated 13', is illustrated in Figures 6, 7 and 8. The tab 13' is provided with an enlarged lower portion 14', corresponding to the portion 14, which is secured by a staple or other fastening 15 to the strap 11 in the same location as the tabs 13, and it is to be understood that a plurality of the tabs 13' will be attached to the strap 11 in the same manner as the tabs 13 are grouped thereon, in Figure 1. The free end of the tab 13' is provided with a single aperture 16'. A bar 19 is provided with the end portions 20 which extend through the tab 13' and are bent inwardly and attached thereto similarly to a staple. The bar 19 bisects the opening 16' and is adapted to engage the shank portion of a hook 17, adjacent its barbed end 18, as illustrated in Figure 6. The tab 13' being formed of a flexible, yieldable material will give relatively to the bar 19 when pressure is exerted thereon so that the barbed end 18 may be released from or engaged with the bar 19 by being passed through the space between the bar 19 and a portion of the tab 13' disposed therebehind.

Obviously the size of the tabs 13 and 13' may be varied as well as the size of the openings 16 to accommodate fly hooks 17 of various sizes or various sizes of fishhooks, not shown. Likewise, the lengths of the bar 19 may be varied for the same purpose.

Various additional modifications and changes are contemplated and may obviously be resorted to and the right is reserved to make such variations as fall within the spirit and scope of the invention as hereinafter defined by the appended claims.

I claim as my invention:

1. A fly hook holder comprising a flexible tab provided with spaced apertures, said tab being foldable between said apertures for inserting the barbed end of a fly hook therethrough or for removing said end therefrom.

2. A holder for fishhooks comprising a supporting member, a tab attached at one end thereto, said tab being provided with spaced apertures adjacent its free end, and said apertures being adapted to engage a fishhook adjacent its barbed end.

3. A fly holder comprising a hatband, a plurality of tabs each attached at one end to said band, and said tabs being of flexible material and each being provided, adjacent its free end with spaced openings for engaging a fly hook, adjacent its barbed end, for mounting a plurality of fly hooks on the hatband.

4. A fishhook holder comprising a tab of flexible material attached at one end to a flexible supporting strap, said tab being provided with spaced apertures, adjacent its free end, for detachably engaging a fishhook adjacent its barbed end.

5. A fly hook holder comprising a flexible tab 25 provided with an aperture and a bar disposed on one side of said tab and bisecting said aperture, said bar having its ends connected to the

tab and forming a holder for detachably engaging a fly hook adjacent its barbed end.

6. A fishhook holder comprising a tab of flexible, yieldable material, and a bar disposed on one 5 side of said tab and having its ends secured thereto for detachably engaging and supporting a fishhook.

7. A fly holder comprising a band having means 10 for detachably and adjustably connecting its ends for attaching the band around the crown portion of a hat or cap, a plurality of flexible tabs each connected at one end to said band, adjacent its upper edge, the free ends of said tabs projecting upwardly from said band beyond its upper 15 edge, and means associated with said free ends for detachably supporting fly hooks.

8. A device as in claim 7, said means comprising spaced openings formed in the tabs for frictionally engaging fly hooks adjacent their shank ends.

9. A device as in claim 7, said means comprising an aperture formed in each of said tabs adjacent its free end, a bar attached at its ends to each of said tabs and extending across its aperture for detachably and frictionally engaging a fly hook.

EDWARD E. SMITH.
